OPHTHALMIC MOUNTING

Samuel E. Bouchard, Rochester, N. Y., assignor
to Bausch & Lomb Optical Company, Rochester, N. Y., a corporation of New York

Application September 30, 1939, Serial No. 297,396

3 Claims. (Cl. 88—47)

The present invention relates to ophthalmic mountings and more particularly to ophthalmic mountings for rimless eyeglasses.

One of the objects of this invention is to provide an ophthalmic mounting having relatively soft bendable straps and a hard, stiff shoe. A further object is to provide a unitary ophthalmic mounting for rimless spectacles in which the ends of the lens shoe will not bend away from the edge of the lens. Another object is to provide an ophthalmic mounting in which a hard, stiff shoe is soldered to a pair of lens straps without a substantial reduction of hardness.

These and other objects and advantages reside in certain novel features of construction and combination of parts, as will hereinafter be more fully described and pointed out.

Referring to the drawing:

Fig. 1 is a fragmentary front elevation of an ophthalmic mounting embodying my invention.

Fig. 2 is a plan view of the lens strap stamping.

Fig. 3 is a side elevation thereof.

Fig. 4 is a section taken on line 4—4 of Fig. 3.

Fig. 5 is a plan view of the lens shoe stamping.

Fig. 6 is a side elevation thereof.

Fig. 7 is a plan view of the two stampings in assembled relation.

Fig. 8 is a section taken on line 8—8 of Fig. 7.

The steps involved in the making of my new lens connection are illustrated in the drawing wherein 10 designates generally a blank or stamping. The ends of the blank 10 form lens straps 12 and 13 which are connected by a narrow neck 14. The strap 12 is provided with a smooth hole 15 and a tapped hole 16 is formed in the strap 13. A ridge or key 17 extends across the narrow neck 14 between the straps 12 and 13.

The shoe 18 is preferably stamped from a rod or wire and is formed with a transverse groove 19 in its rear surface corresponding in size and shape to the ridge or key 17 on the surface of the neck 14.

The shoe 18 is placed against the neck 14 between the straps 12 and 13 so that the ridge 17 engages in the groove 19 and, while in this position, the shoe 18 and blank 10 are soldered or welded together.

The straps 12 and 13 are then bent toward each other past the shoe 18 to engage the opposite surfaces of an ophthalmic lens 20 and the shoe 18 is bent or curved to conform to the edge of the lens 20 as shown in Fig. 1. A spectacle or eyeglass part such as the bridge 21 may be soldered or welded to the lens connection in the manner well known in the art.

The connection may be secured to the lens 20 in any suitable manner. For convenience and simplicity of illustration, I have shown the connection secured to the lens 20 by a screw 22 which passes through the hole 15 in the strap 12, through a hole drilled in the lens 20 and is threaded into the tapped hole 16 in the strap 13. Obviously, other securing means such as the molded rivet illustrated in my Patent No. 1,878,371 issued September 20, 1932, may be used.

It is essential that the lens straps of an ophthalmic mounting be soft and bendable so that they can be made to conform to lenses of different thickness. It is equally essential that the shoe be stiff and rigid so its ends will not bend and back away from the edge of the lens.

In order to incorporate these properties in my new mounting, the blank 10 may be made in a suitable material such as nickel silver. This metal is easily worked and the heat of soldering the shoe 18 to the blank 10 anneals it leaving it freely bendable.

The shoe 18, which must remain stiff, is made of a metal having a high annealing or recrystallization temperature, that is, a metal which will not lose any substantial hardness of stiffness when it is soldered. A number of metals meet this requirement. The alloy known as "Inconel" which contains 78% to 80% of nickel, 12% to 14% of chromium and from 6% to 8% of iron, the chromium-nickel alloys known as "Chromel" and "Nichrome," the hardenable nickel known as "Z-nickel" and some of the austenitic stainless steels are satisfactory. Both the shoe 18 and blank 10 are preferably made from gold-filled stock or they may be plated with a precious, non-corroding metal.

From the foregoing, it will be apparent that I am able to attain the objects of my invention and provide a new and improved lens connection in which the straps are freely bendable while the shoe is stiff and rigid. Various modifications of structure and manner of making as well as suitable changes of material can be made without departing from the spirit of my invention or the scope of the appended claims.

I claim:

1. An ophthalmic mounting for rimless spectacles comprising strap means for engaging a surface of an ophthalmic lens, said strap means having a neck portion overlying the edge of the lens, a shoe member for engaging the edge of the lens, said shoe member being heat joined to said neck portion, said shoe member being formed of a metal having a relatively high re-

- crystallization temperature whereby the metal will not lose any substantial amount of hardness or stiffness by the application of the heat necessary to unite the shoe member to said neck portion, said strap means being formed of a metal which is annealed by the heat of the joining operation whereby the strap means may be bent for adjustment.
2. An ophthalmic mounting for spectacles comprising two straps for engaging opposite surfaces of an ophthalmic lens, a neck portion connecting said straps, and a shoe member for engaging the edge of the lens, said shoe member being heat joined to said neck portion, said shoe being formed of a metal having a relatively high recrystallization temperature whereby the metal will not lose any substantial hardness or stiffness by the application of the heat necessary to unite the shoe to the neck portion, said straps and neck portion being formed of a metal which is annealed by the heat of the joining operation whereby the straps may be adjusted.
3. An ophthalmic mounting for spectacles comprising a pair of straps for engaging, respectively, the opposite faces of an ophthalmic lens, a neck portion connecting said straps, said neck portion having a centrally located recess, a shoe member for engaging the edge of the lens, said member being positioned in said recess and soldered to said neck portion, said member being formed of a metal having a relatively high recrystallization temperature whereby the shoe member will not lose any substantial amount of hardness or stiffness when subjected to the heat required for soldering, the straps and neck portion being formed of a metal which is annealed by the heat of the soldering operation whereby the straps may be bent for adjustment.

SAMUEL E. BOUCHARD.
